Primary Examiner — Elizabeth J Oswecki

(57) **CLAIM**

The ornamental design for a slipper supporting clip, as shown and described.

DESCRIPTION

FIG. 1 is a front view of the slipper supporting clip showing my new design.

FIG. 2 is a side view thereof.

FIG. 3 is a top view thereof.

FIG. 4 is a bottom view thereof; and,

FIG. 5 is a perspective view of a slipper supporting clip shown in a used condition, wherein both the slipper and a butterfly-shaped pendant are depicted in broken lines, which is environmental matter forming no part of the claimed design. All surfaces not shown form no part of the claimed design.
